UNITED STATES PATENT OFFICE

172,727

INFANT'S BIB

Harley E. Pratt, Jr., Seattle, Wash.

Application December 14, 1953, Serial No. 28,050

Term of patent 14 years

(Cl. D3—26)

To all whom it may concern:

Be it known that I, Harley E. Pratt, Jr., a citizen of the United States, residing at Seattle, county of King, State of Washington, have invented a new, original, and ornamental Design for an Infant's Bib, of which the following is a specification, reference being had to the accompanying drawing, forming a part hereof.

In the drawing:

Fig. 1 is a front view of an infant's bib embodying my new design;

Fig. 2 is a back view of the infant's bib;

Fig. 3 is a side elevational view of one side of the infant's bib;

Fig. 4 is a top plan view of the infant's bib.

I claim:

The ornamental design for an infant's bib, as shown.
